UNITED STATES PATENT OFFICE.

EUGEN LANGEN, OF COLOGNE, GERMANY.

APPARATUS FOR THE MANUFACTURE OF COMBUSTIBLE GAS.

SPECIFICATION forming part of Letters Patent No. 258,774, dated May 30, 1882.

Application filed May 25, 1881. (No model.) Patented in England May 2, 1881, No. 1,894; in France May 9, 1881, No. 142,751; in Belgium May 12, 1881, No. 54,617; in Italy May 31, 1881, in Austria July 3, 1881, and in Spain October 6, 1881.

To all whom it may concern:

Be it known that I, EUGEN LANGEN, a citizen of Prussia, residing at Cologne, in the Empire of Germany, have invented an Improvement in Apparatus for the Manufacture of Combustible Gas, of which the following is a specification.

My invention has reference to the production of combustible gas in that description of gas-producers in which the coal or carbonaceous material is caused to descend continuously in a vertical or inclined shaft or retort, at the lower end of which imperfect combustion of the material with air is caused to take place, producing carbonic oxide and nitrogen, while the heat evolved is caused to distill off the volatile constituents of the carbonaceous material in the upper part of the shaft, the different kinds of gases so generated being led off either separately from or together with each other. The presence of the large proportion of nitrogen in the said gases, produced by imperfect combustion of the fuel, is in many cases a source of great inconvenience in the application of these gases for industrial purposes; and one part of the present invention has for its object to effect the production of combustible gases in gas-producers of the kind above referred to in such a manner that from a given quantity of carbonaceous material there shall be generated the maximum quantity of combustible gas more or less entirely free from nitrogen. For this purpose the before-mentioned carbonic oxide and nitrogen gases produced at the lower part of the shaft or retort are entirely or in great part conducted out of the same into a separate chamber or flue, where the carbonic oxide is caused to enter into combustion with heated air, the heat so produced being employed to assist in the conversion of steam or other suitable fluid into combustible gases, that take the place of the carbonic oxide withdrawn from the producer. By preference the combustion of the said gas is caused to take place in an annular chamber surrounding the shaft or retort in which the carbonaceous matter descends, into which annular chamber air previously heated to a high degree by the gaseous products of such combustion is conducted, so as by the combustion to heat the carbona-

ceous contents of the retort to a very high degree, and consequently to distill from the same a maximum quantity of volatile constituents at a point some distance above that where the carbonic oxide and nitrogen are withdrawn, 55 the steam or other fluid being introduced into such highly-heated portion of the carbonaceous matter, in contact with which it becomes decomposed, producing, in the case of steam, pure carbonic oxide and hydrogen, and compounds of the latter with carbon, which, in ascending, mix together with the other carbonaceous gases distilled off from the fuel in the upper part of the retort, and pass away with them to wherever required. If these gases are 60 to be employed for heating purposes only, then steam alone may be employed, as described; but if they are to be used for illuminating purposes, then some hydrocarbon fluid—such as petroleum—may be introduced, together with 65 the steam, to add to the illuminating power of the gases produced.

Various arrangements of gas-producers may be employed for carrying out the above-described method of operating.

Figure 1 of the accompanying drawings shows a vertical section, and Fig. 2 shows a sectional plan on line X X, of the arrangement which I prefer to employ.

The upper part of the apparatus consists of 80 the space A, into which the carbonaceous material is charged, surrounded by an annular space, B, into which the gases produced by distillation escape through holes O in the lower part of A, the parts A and B being conveniently made of metal in one casting. From the space B the gases are conducted away to wherever required by the pipe B'. Below the space A is the shaft or retort C, which is heated externally to a high degree, and in which the 85 distillation of the volatile constituents from the carbonaceous material is consequently carried on as this gradually descends toward the lower chamber, D, where the conversion of the non-volatile constituents into combustible gas 90 is effected by their imperfect combustion with air admitted below. This generating-chamber consists of a cast-iron casing lined with refractory material, its lower end dipping into water contained in a tank, E, and having at 95 100

its middle a fire-grate, F, supplied with air by the pipe F'. The grate may either be so constructed as to prevent the descent of any carbonaceous matter past it, so that the whole of the fuel is converted into combustible gas, in which case the water-tank E would be dispensed with; or when it is not desired to convert the whole of the material into gas the grate may be formed, as shown on the drawings, so as to allow a certain portion of the carbonaceous material to descend past it into the tank E, whence it is withdrawn from time to time. From the top of the chamber D the combustible gases generated therein, being carbonic oxide and nitrogen, are led by flues G into an annular combustion-chamber, H, surrounding the retort C, while at the same time highly-heated air passes into the said chamber by a flue, J. The flues G and J are led up some height in the chamber H, as shown, so as by the combustion of the gas and air to produce an intense heat in the upper part of the retort C and its contents, thereby distilling off from the carbonaceous material the maximum quantity of volatile constituents as it descends, and before it reaches the upper end of the chamber D. The lower part of the annular combustion-chamber H is formed narrower, and from its lowest and coolest point the hot gaseous products of combustion are led by flues K into the regenerator L, where they are caused before escaping to the chimney M to impart a great part of their heat to the incoming air on its way to the combustion-chamber.

The regenerator consists of a chamber divided by a sloping partition, N, formed of metal plates, into two passages, of which L', through which the air passes, is formed of small depth, so as to bring the air into intimate contact with the partition N, while the passage L², into which the hot products of combustion pass, is formed of considerable capacity where the products enter, and gradually narrows toward the exit end. By this arrangement the gaseous products are prevented, on entering, from heating the metal plates N to too high a degree, such as would rapidly destroy them, as is frequently the case with the ordinary construction of regenerators with metallic partitions, while as the products pass toward the narrower end of the passage, after having given off a large portion of their heat, they are brought into more intimate contact with the partition. The plates forming this partition are constructed with ribs on both sides, as shown more clearly in the enlarged cross-section thereof at Fig. 3, so as to offer very extended surfaces for taking up the heat from the products and imparting them to the air. Any accumulation of solid deposit in the passage L² may be readily removed from time to time through the door L³, as shown. Above the chamber D of the producer steam or other suitable fluid is led into the retort C through one or more pipes, Q, in order, as before stated, by its decomposition in contact with the highly-heated carbo-

naceous matter, to form pure carbonic oxide and hydrogen, which mix and pass off with the gases distilled off above. This steam or other fluid is supplied in regulated quantity by the following arrangement: Outside the producer is a tank, P, supplied with the water or other liquid employed, and having several overflow cocks, P', at different levels, so that by opening any one of these cocks the water can be maintained at a corresponding level in the tank. The pipe Q leads from the bottom of the tank in a slanting direction upward through the heated walls of the producer to a level somewhat above the highest level at which water can stand in the tank. Thus according to the level at which the water is maintained in the tank a greater or less volume thereof will be subjected inside the pipe to the heat of the producer, whereby a greater or less quantity of steam will be generated and introduced into the retort. The waste water from the overflow of the tank may be led by a pipe, P², either into a water-space in the bottom of the chamber D, as shown, or into the tank E, or elsewhere.

As before stated, if it be desired to produce a gas of high illuminating power, then some hydrocarbon vapor may be introduced into the retort in a similar manner to that above described.

The operation of the producer is as follows: Assuming the chamber D to have been filled with burning fuel, and that the walls of the retort C have become heated sufficiently by the combustion in the chamber H, the retort is filled up to the apertures O, leading into the annular channel B, with coke, and above that with coal. As the fuel becomes consumed in the chamber D the contents of the retort sink, (their descent may be accelerated by the removal of coke from the tank E, if desired,) the coal in the upper part of the retort descends into the highly-heated compartment C, and the gas production begins, the distilled gases passing through the apertures O into the annular space B, whence they are withdrawn by an exhauster through the pipe B', together with the other gases produced by the decomposition of the steam below. Meanwhile fresh coal is fed at the top. The exhauster action and the chimney-draft are so adjusted to balance each other that none of the distilled gas finds its way to the chimney, and none, or only a limited quantity, of the products of imperfect combustion in the chamber D mingle with the gas distilled above. For producing gas for heating purposes the whole of the carbonaceous matter should be utilized, and in that case such portions of the gas produced in the chamber D as are not required for heating the distillation-space may be drawn off by the exhauster along with the gas distilled off, if the presence of a certain proportion of nitrogen is not objectionable for the purposes to which the gases are applied; but when the gases are used for illuminating purposes the whole of the said products should be drawn off,

either to be wholly burned in the chamber H or to be partly led away to be used for other purposes. It will be evident that the above-described construction of gas-producer may 5 also be applied to the calcining of ores and other minerals, or for carbonizing substances, for which purposes it would only be necessary to mix the necessary proportion of carbonaceous matter with the substances to be operated 10 upon when charging them into the upper end of the retort. In this case the whole of the carbonaceous gases evolved may be caused to pass through the flues G into the chamber H, to be there burned, instead of being partly let 15 off through the openings O above.

Having thus described the nature of my invention, and in what manner the same is to be performed, I wish it to be understood that I am aware it has already been proposed to draw 20 off combustible gases from the lower end of continuous gas-producers to enter into combustion with heated air in passages outside the shaft or retort in which the fuel descends, such arrangements having been described in the 25 specification to Siemens's British Patent No. 972 of 1863, and in that of Attrill and Farmer, No. 569 of 1880; and I do therefore not claim this construction and mode of operation, generally.

30 I am also aware that a patent is being applied for by N. A. Otto for drawing off a portion of the carbonic-acid gas from immediately above the fire-grates of gas-producers, and utilizing the residual heat of the combustion 35 for decomposing steam and other fluids, and I do not claim such method of operating; but I claim—

1. In apparatus for the manufacture of gas, a vertical retort having side openings at its 40 lower part, communicating with passages leading off carbonic oxide and nitrogen into the latter, in combination with means for supplying steam or water to the interior of the retort at a point 45 above the said side openings, substantially as and for the purpose set forth.

2. A gas-producer consisting of a vertical retort having side openings in its lower part,

communicating with passages leading into the upper part of a combustion-chamber surrounding the retort, into the upper part of which chamber also open passages for conducting heated air from a regenerator, and having a third set of passages leading from the bottom of the said chamber to the regenerator for 50 conducting the hot products of combustion from the former into the latter, in combination with the regenerator, substantially as herein described.

3. A regenerator for imparting the heat from 60 the products of combustion to the incoming air, consisting of a chamber divided by a metallic partition, N, into a narrow compartment, L', through which the air passes, and a comparatively large compartment, L², through which 65 the products of combustion pass, the said metallic partition consisting of plates having ribs or projections on both sides, offering very extended surfaces both for taking up heat from the products of combustion and for imparting 70 such heat to the air, substantially as described.

4. The combination of the feeding-chamber A with annular chamber B for leading off the products of distillation, shaft or retort C, the annular chamber H, chamber D, flues G, J, 75 K, and L, and pipe or pipes Q for the introduction of steam or water, all arranged and operating as herein set forth.

5. Apparatus for introducing a regulated supply of steam or water into a gas-producer, 80 the said apparatus consisting of a tank, P, with overflow-cocks P' at different levels, in combination with one or more pipes, Q, leading from the bottom of the tank upward through the producers to a height at or above the highest 85 water-level of the tank, substantially as described.

In testimony whereof I have signed my name to this specification, in the presence of two subscribing witnesses, this 20th day of April, 9c A. D. 1881.

EUGEN LANGEN.
